UNITED STATES PATENT OFFICE

157,843

PILLOWCASE OR SIMILAR ARTICLE

Edwin I. Cohen, New York, N. Y.

Application December 28, 1948, Serial No. 150,409

Term of patent 14 years

(Cl. D92—26)

To all whom it may concern:

Be it known that I, Edwin I. Cohen, a citizen of the United States of America, residing in New York city, county of New York, and State of New York, have invented a new, original, and ornamental Design for a Pillowcase or Similar Article, of which the following is a specification, reference being had to the accompanying drawing, forming part thereof, wherein,

The rear of the pillowcase is identical in appearance to the front shown.

I claim:

The ornamental design for a pillowcase or similar article, substantially as shown and described.

EDWIN I. COHEN.
